UNITED STATES PATENT OFFICE

LEO HASEL, OF FORT BRAGG, CALIFORNIA

SHOE CONSTRUCTION

Application filed October 31, 1929. Serial No. 403,831.

The present invention relates to shoe constructions and particularly to shoes adapted for mountain wear.

An object of this invention is to provide a device for insertion between the insole and the welt of a shoe so as to produce a shoe which will make mountain climbing easier on the feet of the climber.

Another object of this invention is to provide a device of this character which will eliminate the splitting of the leather on the ball of the foot by reason of the extremely sharp bends to which the shoe is subjected in mountain climbing.

The above and various other objects and advantages of this invention will in part be described in and in part be understood from the following detailed description of the present preferred embodiment, the same being illustrated in the accompanying drawings wherein:—

Fig. 1 is a longitudinal sectional view taken substantially through the middle of a shoe showing an inlay constructed according to this invention mounted thereon;

Fig. 2 is a longitudinal sectional view of a modification of this device;

Fig. 3 is a longitudinal sectional view showing a plurality of inlays mounted thereon; and

Fig. 4 is a transverse section of this device; and

Fig. 5 is a transverse section of the device showing a further modification.

Referring to the drawings the numeral 10 designates the upper portion of a shoe of standard construction having a heel 11 mounted thereon. The shoe 10 is also provided with the usual outsole 12 and an insole 13 which are of the usual construction. An inlay 14 is mounted between the insole 13 and the outsole 12 substantially forward of the instep portion 15 and adapted to extend beneath the ball of the foot as indicated at 16.

The inlay 14 conforms to the configuration of the shoe at the side edge portions thereof, and the front and rear portions of the inlay are preferably tapered so that the front and rear portions thereof will fit snugly between

the insole 14 and the outsole 12. The thickest part of the inlay is preferably at the ball portion of the foot and when the inlay has been inserted between the insole and the outsole a relatively enlarged ball portion will result, while at the same time not disturbing the inner configuration of the insole.

When the inlay has been inserted in the shoe the ball portion of the shoe will lie in a plane below the forward end of the shoe as indicated at 17, thus presenting not only an enlarged wearing portion at the point where the greatest amount of wear will occur, but also forming a ridge which will facilitate the wearer in climbing over rocks or the like, and at the same time eliminate unnecessary bending of the sole of the shoe.

A modification of this device has been shown in Fig. 2 wherein a substantially elongated inlay 18 has been inserted between the insole 13 and the outsole 12, and the rear portion of the inlay has been extended rearwardly so as to be positioned between the heel and the insole.

In the modification shown in Fig. 2 the ball portion of the outsole has not been arched downwardly to present a sharp ridge portion as indicated at 17 in Fig. 1, but the instep of the shoe has been substantially reinforced so that the instep will not be injured from projecting stones or the like.

In Fig. 3 there is disclosed a combination of inlay members so arranged as to increase the arcuate ridge 17 at the ball of the shoe and turn the toe portion thereof upwardly. In this modification the configuration of the insole has not been altered to a great extent but the ball portion of the sole has not only been doubly reinforced but an enlarged ball portion has been formed within the outsole.

As shown in Fig. 5, the construction of the inlay may be further modified by beveling the side portions of the inlay 14 so as to conceal the inlay between the outsole and the upper portion of the shoe.

It will, of course, be understood that various combinations of the inlay members may be used and that any number of inlays may be inserted between the insole and the outsole but depending only upon the use to which

the shoe will be put and the contour of the ground or mountain side.

As shown in the drawings, the forward edge of the wedge or inlay will be positioned spaced rearwardly from the forward edge of the shoe. It is, of course, understood that various changes and modifications may be made in the details of construction and design of the above specifically described embodiment of the invention without departing from the spirit thereof, such changes and modifications being restricted only by the scope of the following claim.

What is claimed is:-

- 15 In a shoe construction having an insole and an outsole, a member disposed between said insole and outsole, said member tapering longitudinally and transversely from a point intermediate the marginal edges thereof, the
- 20 thickest portion of said member being positioned at substantially the junction of the instep and the ball portion of the shoe, said member providing a transversely disposed rib at the junction of the instep and the ball of
- 25 the shoe, the outsole being disposed on an upward and forward inclination.

In testimony whereof I hereunto affix my signature.

LEO HASEL.
